UNITED STATES PATENT OFFICE.

FRANK TRAVAGLINI, OF PHILADELPHIA, PENNSYLVANIA.

STRINGED MUSICAL INSTRUMENT.

Application filed March 10, 1924. Serial No. 697,977.

My invention relates to stringed musical instruments and its object is to provide a stringed instrument embodying the features of a banjo and guitar and which is especially adapted for playing orchestral music.

This object, and other advantageous ends which will be described hereinafter, I attain in the following manner, reference being had to the accompanying drawing in which

10 Figure 1 is a plan view of an instrument constructed in accordance with my invention.

Figure 2 a left hand edge view of Figure 1, and

15 Figure 3 an enlarged section on line 3—3 of Figure 1.

Referring to the drawings, 1 indicates a guitar-shape body, hereinafter called a guitar body having an extension 2 forming a 20 banjo-shape body hereinafter called a banjo body. The wall of the upper part of the guitar body merges into the wall of the banjo body at 3, and the wall of the narrow part of the guitar body merges into the wall 25 of the banjo body at 4, and said walls form a continuous outer wall or frame as best seen in Fig. 1. A ring 5, conforming to the contour of the guitar and banjo bodies fits over them and is adapted to securely hold 30 a sheepskin-covering 6 thereon having a reinforced beaded edge 7 which is engaged by ring 5. Tightening hooks 8 are secured to the banjo and guitar bodies by screws or otherwise. A guitar neck 9 is secured to the 35 upper and lower part of the guitar body by passing an extension piece 10 through the body and connecting it to the lower part by a screw. A guitar finger board 11 is secured to neck 9 and preferably extends a short distance over the body. The tail-piece 12, 40 bridge 13, strings 14 and pegs 15 are connected to the guitar body and its neck in the ordinary way. A banjo neck is secured to the banjo body by passing an extension 17 45 through the upper and lower part of the body, similar to guitar neck 9, and a banjo finger board 18 is secured to the neck. The tail-piece 19, bridge 20, strings 21 and pegs 22 are connected to the banjo body and its 50 neck in the ordinary way.

With the instrument above described, various kinds of music, such as required in an orchestra, may be produced by simply changing the positions of the hands. The 55 tones from the guitar are of the banjo character which are well adapted for dance

music. By having a banjo and guitar body integral the vibrations from the banjo pass to the body of the guitar and vice versa, thus producing short, deep and mellow tones 60 from either set of strings.

Having thus described my invention, what I claim as new and desire to secure by Letters Patents is:—

1. A stringed musical instrument characterized by having an elongated sound body formed with oppositely curving top enlargements; one of the top enlargements being circular in form and curving topwardly beyond the other of the enlargements; a pair 70 of parallel finger boards having extensions passing through the body on lines corresponding respectively to the longitudinal center of the elongated sound body and a diametrical center of the circular top enlargement thereon; having a sheepskin head on the body, and means to tighten the head, substantially as described.

2. A stringed musical instrument characterized by having an elongated sound body 80 formed with oppositely curving top enlargements; one of the top enlargements being circular in form and curving topwardly beyond the other of the enlargements; a sheepskin head on the body; a guitar neck having 85 an extension passing through the elongated sound body on its longitudinal center line; and a banjo neck having an extension passing through the center of the circular extension, parallel to and extending slightly 90 beyond the guitar neck.

3. In a stringed musical instrument an elongated sound body formed with oppositely curving top and bottom enlargements; one of the top enlargements being circular 95 in form and curving topwardly beyond the other of the top enlargements; a sheepskin covering for the elongated body and the circular enlargement thereon and provided with a beaded edge; a member engaging said 100 beaded edge and extending entirely around the elongated body and the circular enlargement thereon; means for holding said member in adjusted position, a banjo neck having an extension passing through the 105 center of the circular extension, parallel to and extending slightly beyond the guitar neck.

In testimony whereof I have signed my name to this specification.

FRANK TRAVAGLINI.
